UNITED STATES PATENT OFFICE

2,442,043

LOADING DEVICE

Albert R. Henry, Salina, Kans., assignor to Henry Manufacturing Company, Inc., Topeka, Kans., a corporation of Kansas

Application November 18, 1944, Serial No. 564,095

6 Claims. (Cl. 214—139)

1

This invention relates to improvements in loading devices and refers more specifically to loading attachments for use with standard tractors.

The principal object of the present invention is the provision of a loading attachment that is adjustable to fit many of the various makes and sizes of standard farm tractors now in general use.

Another object is the provision of a novel cable winding drum having means for causing the cable to wind in an even helical form on the drum.

A further object is the provision of a loading device having a combination bucket and fork for general purpose use about the farm.

Other objects are simplicity and economy of construction, ease and rapidity of operation, and adaptability for quick adjustment to fit various sizes and makes of tractors.

With these objects in view, as well as other objects which will appear during the course of the specification, reference will be had to the drawings wherein:

Figure 1 is a side elevation of a loading device embodying this invention, shown with the bucket in the lowered loading position in solid lines and in the raised, dumped position in dotted lines.

Fig. 2 is a plan view of the loader with the bucket lowered and parts broken away.

Fig. 3 is a front elevation of the loader with parts broken away and with some parts omitted.

Fig. 4 is an enlarged plan view of a portion of the boom and the special bucket carried thereby.

Fig. 5 is a sectional view taken on line V—V of Fig. 4.

Fig. 6 is a sectional view taken on line VI—VI of Fig. 4.

Fig. 7 is an enlarged fragmentary, vertical section taken on line VII—VII of Fig. 1.

Fig. 8 is a sectional view showing the cable lift and its associated parts.

Fig. 9 is an enlarged sectional view taken on line IX—IX of Fig. 3.

Throughout the several views like reference characters refer to similar parts and the numeral 16 designates a tractor of any of the standard types used on the farm. The tractor shown is of the row crop type having a frame 18 mounted on the rear driving wheels 20 and the dual front steering wheels 22. Frame 18 carries the usual power unit (not shown) provided with a power take-off shaft 24 and includes the rear axle housing 26 which carries the axle 28 and has a differential housing 30. Housing 30 carries a seat 32 for the operator who is in convenient reach of the steering wheel 34 which is mounted on the steering rod 36 having a stabilizing rest post 38.

The loading attachment adapted to be carried by and operated by the tractor power unit com-

2

prises a substantially vertically disposed frame 40 having a pair of out-turned channel track members 42 which are joined together at their upper extremities by a cross head bar 44 braced thereto by means of diagonally disposed bars 46. Cross bar 48 joins together members 42 intermediate their ends and is securely joined thereto by means of gusset plates 50. This frame 40 is pivotally attached to tractor frame brackets 52 by means of pins 54 which pass through holes formed through bracket 52 and bracket plate 56 which is rigidly secured to channel track member 42. The bracket plate 56 has a vertically disposed series of holes 57 to permit vertical adjustment of the frame 40. Each channel member 42 is provided with an ear 58 to which the angle iron bar 60 is pivoted by pin 62. Bar 60 is made up of two angle iron sections joined together by bolts 64 which may be adjusted to different holes of the series 66 so as to shorten or lengthen the bar to vary the angle of inclination of the frame 40.

Bar 60 is secured at its lower end to a bracket 68 which in turn is secured to the axle housing 26. This bracket 68 is provided with a series of holes 70 for receiving bolts 72 so as to permit transverse adjustment of the bracket on the axle housing. Another bracket member 74 disposed on the opposite side of the axle housing 26 and secured thereto by bolts 76 are joined together by means of a depending bracket member 78 having two spaced apart ears 80 in which is securely mounted a transverse pin 82. This bar 60, when lengthened as described above, will increase the forward inclination of the track members 42, thus causing the positioning of the bucket at a greater distance from the tractor when it is in the raised position.

The boom 84 is of substantially U-shaped form having side arms 86 and a cross header 88. Adjacent and to the rear of the header 88 at each side of the boom, is a bracket 90 secured to the side arms 86 and carrying a roller 92. These rollers are adapted to respectively engage the outwardly turned channel tracks 42 for movement therein. The lower end of the channels 42 are closed at 94 to prevent the rollers from moving out of the channel. Side arms 86 of the boom are made up of a pair of spaced apart angle irons 96. It will be noted that the bracket 90 has a transverse lug 98 which extends between the angle irons 96 and is secured thereto by means of bolts 100 which may be adjusted along the series of holes 99 to vary the position of bracket 90 relative to the side arms 86. The rear ends of side arms 86 extend beyond the bracket 78 and the pin 82 extends between the angle irons 96 so that the side arms have a sliding movement for longitudinal adjustment as the boom is raised.

By referring to Fig. 1, it will be noted that a

stop block 104 rests against pin 82 when the bucket carried by the boom is in the loading position so that the thrust against the bucket during the loading operation is transmitted to the pin 82 through the side arms 86.

Stop block 104 is positioned between the angle irons 96 and is secured by bolts 101 which are fitted through holes 102 formed in bars 96. Holes 102 are in a series of sufficient number to permit adjustment of the stop block along the angle irons.

The rearward ends of the angle irons 96 are spaced apart by a block 106; also the intermediate portions of the angle irons 96 are provided with reenforcing, spaced apart blocks 108. The boom 84 is provided at its forward end with forwardly extending arms 110 between which is mounted a bucket 112. This bucket is pivoted to arms 110 by pins 114 in such a manner that the bucket when loaded and in the raised position, tends to tilt forwardly to release the load.

Latch means 115 for securing the bucket against tilting is best shown in Figs. 5 and 6 and comprises a detent member 117 securely attached to the rear of the bucket by bolts 119 and has a cross bar 116 which is adapted to be engaged by a latch member 118 which is rigidly mounted on shaft 120 rotatably mounted in bearings 122 which are integral with cross header 88. Shaft 120 extends transversely of the latch to extend through a bearing 124 and is provided at its outer end with a rigidly attached operating arm 126 which is normally held in the forward position by means of a compression spring 128 positioned between an arm 127 of the operating arm 126 and the top side of side arm 86. This spring causes the latch member to normally engage cross bar 116. An operating cable 130 secured to the free end of arm 126 is secured at its other end to a transverse bar 132 secured to rod 36. This operating cable may be engaged by the operator to release the bucket at any point above the ground. Normally it is operated when the bucket is in the raised position as shown in Fig. 1.

The power for raising and lowering the boom and bucket is from the tractor power take-off shaft 24. This power take-off shaft is now common structure on substantially all tractors and may vary slightly in position and direction; however, they are all adapted to furnish power for handling this loader. In the type of tractor shown, the pulley wheel 134 is rigidly attached to the power take-off shaft 24 and is operatively connected with the pulley wheel 136 of a power transmission member 138 by means of a belt 140. This power transmission member is securely attached to cross bar 48 and is provided with a shaft 142 which carries the pulley 136. This power unit is provided with a clutch member 144 which is adapted to be operated to drive shaft 146 on which is mounted sprocket wheel 148. This sprocket wheel is operatively connected with a sprocket wheel 150 by sprocket chain 152. Sprocket wheel 150 is securely attached to the central portion of a cable winding drum 154, which in turn is mounted for rotation in bearings 156 secured to track member 42.

The boom 84 is raised and lowered by means of a pair of cables 158 disposed at opposite sides of frame 40, each being similarly mounted as shown in Fig. 8. One end of the cable is fixed to the head bar 44 by means of a clamp member 160, then extends downwardly to pass around a sheave-wheel 162 rotatably mounted in brackets 164 which extends rearwardly from the cross header

88. The cable then extends upwardly over a sheave wheel 166 which is rotatably carried by a pin 168 mounted in header bar 44, thence downwardly to winding drum 154 to which it is rigidly attached. This cable is of sufficient length to permit the bucket 112 to be moved to the ground position. The leverage obtained by the use of this type of lift is two to one so that the load may be easily lifted.

Difficulty has been previously encountered in producing a lift of this character wherein the cable will definitely wind in a uniform helical path about the winding drum and to insure this proper winding of the cable so that there will be no piling up of the cable on the drum, the following mechanism is provided.

The trunnions 170 of the drum are mounted in the bearings 156 so as to prevent longitudinal movement of the drum and adjacent each end of the drum is securely affixed a disk 172 having a frusto-conical inner face against which the cable 158 rests when the bucket is in the lowered position. This cable is attached to the drum by means of a cable fastening means 174 such as shown in my application, Serial No. 551,015, filed August 24, 1944. Adjacent each of the disks 172 is a complementary disk 176 which is urged outwardly against the cable 158 by means of a compression spring 178 so that these springs 178 are mounted freely on drum 138 whereby each rests against its respective disk 176 and the sprocket wheel 150. As the cable is wound on the drum, disks 176 move inwardly to compress springs 178, thus insuring the proper aligning of the cable during the winding operation. The cable securing means 174 is so positioned and constructed that during the winding of the first convolution, the cable 158 will always be forced inwardly so as to start the proper positioning of the cable on the drum. In many instances, however, the cable will not be totally unwound and may always have at least one full convolution on the drum 138.

During the dumping operation, it is necessary to provide shock absorbers 180 to prevent damage to the machine, due to the sudden drop of the heavy load. Each shock absorber comprises a cylindrical member 182 pivoted at 184 to brackets 186 mounted on angle bar 96. This cylindrical member 182 is recessed and provided with a cap 188 through which extends a rod 190 about which is mounted a compression spring 192. Spring 192 is disposed between cap 188 and a collar 194 rigidly attached to rod 190 so that as the rod 190 is moved outwardly, it will compress spring 192. Rod 190 is connected by means of chain 196 through fastening means 198 to the rear wall of bucket 112 above pivot point 114 so that as the bucket is dumped, as shown in dotted lines in Fig. 1, the chain will be extended and the spring compressed to act as a shock absorber to absorb the shock due to the dropping of the load. The shock absorbers at opposite sides of the boom are identical in shape and construction and are of sufficient strength to properly absorb the shock of the bucket, due to its drop during the dumping operation.

The operator controls the clutch of the power transmission 138 by means of a hand lever 200 pivoted at 202 to a vertical standard 204 rigidly carried by angle iron 96. An operating rod 206 is pivoted to lever 200 at 208 and extends forwardly to operatively engage a suitable clutch operating mechanism (not shown).

The bucket 112 as shown throughout the various views is of special construction and consti-

tutes a combined bucket and fork. The fork 210 comprises a transverse bar 212 having a series of comb-like teeth 214 extending in spaced apart parallel relation therefrom as clearly shown in Fig. 2. This fork is secured to the bucket 112 by means of bolts 216 and also by detents 218 welded to the under side of the teeth 214. All that is necessary to separate the fork from the bucket is to remove bolts 216 and move the fork slightly forward to release the detents 218.

It is quite apparent that many other types of attachments might be utilized in conjunction with this loader for the purpose of handling various types of materials.

It is quite apparent that this loading attachment is easily operated and controlled by one man from the seat of the tractor.

Due to slightly different structural features of the various types of farm tractors, it may, in some cases, be found necessary to make slight changes in the structure of the attachment. However, this may be accomplished without departing from the spirit of the invention.

Having thus described the invention, what I claim as new and desire to be secured by Letters Patent is:

1. A loading attachment adapted to be mounted on and operated by a tractor, comprising a vertically disposed frame pivotally mounted intermediate its top and bottom to the front end of said tractor, means for adjustably securing said frame in a plurality of angled relations to said tractor and against movement relative thereto, a boom shiftably mounted at its forward end along said frame and slidably mounted at its rear portion on pins fixed to said tractor, a bucket tiltably mounted on the forward end of said boom, means for normally securing said bucket in the loading position, a manually controlled means for raising and lowering said boom, and means for releasing said bucket securing means.

2. A loading attachment adapted to be mounted on and operated by a tractor, comprising a vertically disposed frame pivotally mounted intermediate its top and bottom to the front end of said tractor, means for adjustably securing said frame in predetermined inclined positions against movement relative to said tractor, a boom shiftably mounted at its forward end along said frame and slidably mounted at its rear portion on pins fixed to said tractor, a bucket tiltably mounted on the forward end of said boom, means for normally securing said bucket in the loading position, a manually controlled means for raising and lowering said boom, and means for releasing said bucket securing means to permit the bucket to tilt, and resilient means to limit the tilting of said bucket.

3. A loading attachment adapted to be mounted on and operated by a tractor, comprising a vertically disposed frame having side track members pivotally mounted intermediate their ends to the front end of said tractor, longitudinally adjustable means for securing said frame in predetermined angled relations to the tractor and against movement relative to said tractor, a boom shiftably mounted at its forward end in said track members and slidably mounted at its rear portion on pins fixed to said tractor, a bucket tiltably mounted on the forward end of said boom, means for normally securing said bucket in the loading position, a manually controlled means for raising and lowering said boom and means for releasing said bucket securing means.

4. A loading attachment adapted to be mounted

ed on and operated by a tractor, comprising a vertically disposed frame having side track members pivotally mounted intermediate their ends to the front end of said tractor, longitudinally adjustable means extending to the rear of said tractor for engaging and securing said frame against movement relative to said tractor, a boom shiftably mounted at its forward end in said track members and slidably mounted at its rear portion on pins fixed to said tractor, a bucket tiltably mounted on the forward end of said boom, stops carried by said boom to engage said pins for limiting the backward movement of said boom, means for normally securing said bucket in the loading position, a manually controlled means for raising and lowering said boom, and means for releasing said bucket securing means.

5. A loading attachment adapted to be mounted on and operated by a tractor, comprising a frame having guides pivotally carried in a substantially vertical position by the front end of said tractor and being vertically adjustable relative thereto, longitudinally adjustable means for securing said frame against movement on its pivots, a boom shiftably mounted at its forward end in said guides, and mounted at its rear end on pins fixed to said tractor and transversely adjustable relative to said tractor, a bucket tiltably mounted on the forward end of said boom, latch means for normally securing said bucket in the loading position, manually operable means for releasing said latch means, and a cable operable by said tractor to raise and lower said boom.

6. In a device of the character described, a cable winding apparatus including a rotatably mounted drum having a centrally disposed driving means whereby it is selectively driven in either direction, a cable having one of its ends attached to one end of said drum to wind thereabout and its other end attached to the other end of said drum to wind in the opposite direction, a collar mounted on said drum at each side of said driving means with a helical spring disposed between the driving means and the respective collars to constantly urge the collars against the respective cables whereby the cable will be caused to form even closed convolutions about said drum as the driving means is operated.
